200,054

COMBINED TUMBLER AND HOLDER THEREFOR

Bernard F. Swartz, 901 Mifflin St., Orville C. Dore,
R.D. 2, Frank S. Bagshaw, 303 Reynolds Ave., and
Richard C. Coffman, R.D. 1, all of Huntingdon, Pa.

Filed Apr. 17, 1964, Ser. No. 79,545

Term of patent 14 years

(Cl. D44—10)

FIG. 1.

FIG. 2.

FIG. 3.

FIG. 4.

FIG. 1 is a front elevation of a combined tumbler and holder therefor showing our new design.

FIG. 2 is a side elevation;

FIG. 3 is a top plan view; and

FIG. 4 is a rear elevation.

We claim:

The ornamental design for a combined tumbler and holder therefor, as shown.
